CLAIM

What is claimed is the ornamental design for a thermotherapeutic pad, as shown and described.

DESCRIPTION

FIG. 1 is a top perspective view of a thermotherapeutic pad. FIG. 2 is a bottom perspective view of the thermotherapeutic pad.

FIG. 3 is a front view of the thermotherapeutic pad.

FIG. 4 is a side view of the thermotherapeutic pad.

FIG. 5 is a rear view of the thermotherapeutic pad.

FIG. 6 is a top view of the thermotherapeutic pad.

FIG. 7 is a bottom view of the thermotherapeutic pad; and, FIG. 8 is perspective view of the thermotherapeutic pad wrapped around a person's arm in use.

The broken lines in FIG. 8 are for the purpose of depicting environment and form no part of the claimed design.

1 Claim, 5 Drawing Sheets
